UNITED STATES PATENT OFFICE

171,287

COMBINED RECEPTACLE HOLDER AND COASTER

Cruz R. Alvarez, Mesilla, N. Mex.

Application June 2, 1953, Serial No. 25,290

Term of patent 14 years

(Cl. D44—10)

To all whom it may concern:

Be it known that I, Cruz R. Alvarez, a citizen of the United States, residing at Mesilla, State of New Mexico, have invented a new, original, and ornamental Design for a Combined Receptacle Holder and Coaster, of which the following is a specification, reference being had to the accompanying drawing, forming a part hereof.

Fig. 1 is a perspective view of a combined receptacle holder and coaster showing my new design; and,

Fig. 2 is another perspective view thereof.

I claim:

The ornamental design for a combined receptacle holder and coaster, as shown.

CRUZ R. ALVAREZ.
